UNITED STATES PATENT OFFICE.

JUNJI YANO, OF LOS ANGELES, CALIFORNIA.

ALARM FOR STRONG BOXES.

1,427,507.

Specification of Letters Patent. Patented Aug. 29, 1922.

Application filed July 22, 1921. Serial No. 426,833.

To all whom it may concern:

Be it known that I, JUNJI YANO, a subject of the Emperor of Japan, residing in the city and county of Los Angeles and 5 State of California, have invented a new and useful Alarm for Strong Boxes, of which the following is a specification.

This invention has relation to an improved alarm for money-boxes, grips, 10 satchels, and other articles of similar character, and its objects are to provide means for indicating, by audible signal, such as the ringing of a bell, when the money-box, or similar article, is lifted or displaced from 15 its position, and to provide a signal of this character, which cannot be readily prevented from ringing, except by a key especially for the purpose, or by replacing the money-box or other article in its normal position.

20 Other objects and advantages may appear in the subjoined detail description.

In the drawings: Figure 1 is a top plan view of the base section of a strong-box embodying my invention. Fig. 2 is a side view 25 of the same. Fig. 3 is a perspective view of the strong-box constructed in accordance with this invention. Fig. 4 is a bottom plan view of the same. Fig. 5 is an enlarged and detail plan view of the actuating mechanism 30 for ringing the alarm. Fig. 6 is a vertical and sectional view of the alarm-actuating mechanism. Fig. 7 is a fragmentary view showing the releasing means for the alarm.

Referring to the drawings, the box 11 is 35 provided with a base-plate 12 carrying my improved alarm mechanism, and secured to the box, by screws 13, and provided with apertures 14. On the top 15, of the base plate, I have mounted the bell 16, and 40 brackets 17. Tripping levers 18, 19, 20 and 21, are pivotally connected to brackets 17. To the longer arm 22, of each tripping lever, I have fixed a plunger 23, the plungers sliding in apertures 14, and extending there- 45 through, when the box is lifted from its position. A bracket 24, mounted on the base-plate, has pivotally connected thereto, the rocking lever 25, having a weighted arm 26, extending over the free extremities 27, of 50 tripping levers 18, 19, 20 and 21, and having the opposite end 28 arranged for engaging the bell-hammer 29, when the weighted end 26 is released. Springs 30 bear upon the tripping levers adjacent to the plungers, 55 and, when the box is lifted, actuate the tripping levers, which thereupon force the

weighted end 26 upward, and release the bell-hammer 29.

For operating the bell-hammer, I provide an actuating mechanism, consisting of a main-spring 31, having one end connected to a fixed shaft 32 in casing 33, and the opposite end fixed to shaft 34, having a rectangular end 35, for winding with a key (not shown), and having a ratchet wheel 36 fixed thereto. A gear wheel 37 is mounted to rotate independently upon shaft 34, and has a spring-actuated pawl 38, in engagement with ratchet wheel 36. When gear-wheel 37 is held against rotation, then a key 40 may be used to turn the shaft 34, and thereby wind up spring 31. A countershaft 39 has mounted thereon, the pinion 40, in engagement with wheel 37, and a gear-wheel 41, in engagement with a pinion 42 on shaft 43. A ratchet escapement wheel 44 is mounted on shaft 43, and rotates synchronously with pinion 42. An escapement pawl 45, on shaft 46, is in operative engagement with the escapement wheel, and the bell-hammer 47 is fixed to shaft 46. With this construction, it may be seen that whenever the bell-hammer is released, the train of gears is 50 also released, and the power of the spring is then utilized to operate the bell-hammer. 55

At times it may be desired to handle the box and avoid ringing of the bell. To accomplish this, I provide a key shaft 48, mounted in the standard 49, and having a pawl 50, adapted to engage with the escapement wheel. A key socket 51 is provided for operating this key shaft. I further provide a series of blind key-sockets 52, which serve to confuse one who would tamper with the alarm mechanism surreptitiously. 90

In use, the alarm is set by inserting a key in socket 51, and turning shaft 48 so that pawl 50 releases the escapement wheel. The box is then placed so that its base-plate rests upon some support, and, having more 100 weight than what will off-set the force of springs 30, the tripping levers are released, causing the weight on lever 25 to force the free end 28 into engagement with bell-hammer 29. 105

From the foregoing it may be seen that I have provided simple and efficient apparatus for ringing an alarm when the containing object is handled, the device being applicable to other than strong-boxes. 110

It may be further noted that, when the alarm is set for operation, the box cannot

be raised or carried without operating the alarm, for each plunger is spring-actuated to protrude from the bottom of the base-plate, so that all, or any one of them, when 5 extended, will, through its corresponding lever, actuate the rock-lever which releases the bell-hammer. Therefore, all of the plungers must be pressed inward to cause the rock-lever to move to inoperative position. Consequently, the box cannot be tampered with without ringing the alarm, except that the operator has a key which will 10 turn the detent member 50 to operative position.

15 What is claimed is:

1. The combination with a strong-box base plate having a plurality of apertures, of a bell on the upper side of the base-plate, a plurality of brackets projecting upwardly 20 from the base-plate, tiltable levers pivotally connected to the brackets and having relatively long and short arms, plungers pivotally connected to the long arms of the tiltable levers and projecting normally through 25 the apertures in the base-plate, springs having their middle part connected to the base-plate and their extremities bearing upon the tiltable levers adjacent to the plungers, a spring-actuating mechanism mounted on the 30 base-plate and having a key-winding shaft, a bell-hammer operated by the spring actuating mechanism and arranged to strike the bell, a rock-lever bracket mounted on the base-plate, a rock-lever pivotally connected

to the rock-lever bracket, a weighted arm of 35 said rock-lever projecting over the ends of said tiltable levers, the opposite arm of the rock-lever being arranged as a detent for the bell-hammer, a stop lever for the bell-hammer, a shaft for the stop-lever adapted 40 to be actuated by a key, barrel sockets for the key shafts, and a plurality of blind barrel sockets adjacent to the first-named sockets.

2. The combination with a strong-box 45 base-plate and an alarm device mounted thereon, of a spring-actuated mechanism for operating the alarm device, a rock-lever having one arm serving as a detent for the alarm device, a weight on the opposite end of the 50 rock-lever which serves to hold the detent arm in engagement with the alarm device, a plurality of tiltable levers fulcrumed with relatively short arms and long arms, said short arms having their extremities lying beneath the weighted arm of the rock-lever, 55 springs bearing upon the long arms of the tiltable levers and operative to actuate the tiltable levers and thereby lift the weighted end of the rock-lever, and plungers pivotally 60 connected to the tiltable levers and extending through the base-plate, and serving to force the spring-pressed arms of the tiltable levers to inoperative position when pressed inward by an exterior object. 65

In testimony whereof, I hereunto affix my signature.

JUNJI YANO.
